UNITED STATES PATENT OFFICE.

GEORGE BURFORD ANDERSON, OF DETROIT, MICHIGAN.

WRENCH.

Application filed January 21, 1921, Serial No. 433,937. Renewed January 28, 1924.

To all whom it may concern:

Be it known that I, GEORGE BURFORD ANDERSON, a subject of the King of Great Britain, and resident of Detroit, Michigan, have invented certain new and useful Improvements in Wrenches, of which the following is a specification.

The invention relates to improvements in wrenches as described in the present specification and shown in the accompanying drawings that form a part of the same.

The invention consists essentially of the novel construction and arrangement of parts whereby a wrench of the type in which the adjusting nut is movable laterally by means of a lever, is provided with means for transforming the rotary pressure of said lever to a longitudinal pressure against said nut.

The objects of the invention are to facilitate the operation of the wrench by reducing to a minimum the friction between the movable parts, to lengthen the life of the wrench, to permit of the provision of a new disc from time to time without the necessity of replacing the nut, and generally to provide a wrench which will be inexpensive to manufacture, efficient in operation, and durable.

In the drawings Figure 1 is a side view of the wrench, a portion being broken away to show the arrangement of the otherwise concealed parts.

Figure 2 is an edge view of the wrench.

Figure 3 is a cross sectional view taken on the line A—A of Figure 2.

Figure 4 is a side elevation of the movable jaw.

Figure 5 is an end view of the movable jaw.

Figure 6 is a perspective view of the disc interposed between the adjusting nut and the lever used to effect the lateral movement of said nut.

Like numerals of reference indicate corresponding parts in the various figures.

Referring to the drawings A represents the main portion of the wrench, comprising a head 1 having an integral jaw 2 from one side thereof and an integral handle 3 from the side opposite the rigid jaw 2.

4 is a movable jaw having a tongue 5 slideable in a lateral opening 6 through the head 1 to permit of adjusting said jaw 4 in relation to said jaw 2, said tongue 5 being threaded as at 7 along the under edge thereof.

8 is a worm nut rotatably mounted in a transverse cut 9 in the head 1 on a fixed pin 10, said nut being somewhat shorter than

said cut or gap 9 and being adapted to mesh with the threads 7 of the tongue 5 and upon rotation imparting longitudinal movement to the movable jaw 4 in relation to the rigid jaw 2.

As the gap 9 is of greater length than the nut 8 it will be apparent that said nut, the tongue 5 and the jaw 4 are movable laterally in relation to the jaw 2 without the necessity of rotating said nut, thus making it possible to adjust the pressure of the jaws on the nut or other object being gripped without rotating the screw 8.

The thread of the nut 8 is preferably of substantially disc form, that is to say, having one of its walls, designated by the numeral 8^a, of straight construction and having its other side provided with a slight bevel as at 8^b, so that pressure brought to bear on the end of said nut corresponding to the bevelled side of the thread will tend to lock said thread firmly into the notches or threads in the tongue 5 and thus eliminate all possibility of said tongue and said nut being forced apart.

12 is a lever having offset parallel end arms 13 adapted to project over opposite sides of the section A and being pivoted intermediate of their length to said section 85 and the side of the gap 9 adjacent to the handle as indicated by the numeral 14, said arms being provided with comparatively small inwardly offset fingers 15 adapted to bear towards the end of the worm nut 8 upon the outer end of the lever being drawn towards the handle 3.

16 is a coil spring encircling the pin 10 between the end of the nut 8 farthest from the fingers 15 and the end of the gap 9 and exerting pressure on said nut to hold the jaw 4 to its extended position.

It is necessary to provide a means for eliminating the friction between the nut 8 and the fingers 15 caused by the rotary motion 100 imparted to said fingers upon the compression of the lever 12 and to this end a disc 17 of greater thickness than the width of an individual thread of the tongue 5 and having a concaved end 18 adapted to substantially 105 follow the general contour of the under side of the tongue 5, is loosely mounted on the pin 10 between the end of the nut 8 and the fingers 15 so that when the lever 12 and the handle 3 are compressed said washer or disc 110 will receive the rotary or frictional pressure of the fingers 15 while the nut 8 will receive

even pressure over the whole end surface thereof.

In the operation of the invention the jaws are first adjusted by means of the nut 8 to approximately the size of the object to be turned and the wrench is grasped with the handle 3 next the palm of the hand.

The jaws are then placed over the object to be turned and the lever 12 drawn inwardly towards the handle 3 causing the fingers 15 to bear with a rotary movement against a comparatively small portion of the surface of the disc 17 which permits of even longitudinal pressure being imparted to the nut 8 forcing said nut and consequently the jaw 4 towards the rigid jaw 2 and closing said jaws firmly over said object.

To take a fresh grip on the object the pressure on the lever 12 is relieved and the wrench swung around to the desired position when the jaws are again brought together to firmly engage the object by renewed pressure on said lever. The jaws 2 and 4 may be provided with notches 19 thus

permitting of grips being taken either on the flat or corners of a nut as desired.

What I claim is:—

A wrench comprising a handle terminating in a head forming one jaw and having a substantially rectangular worm slot and a track 30 for the movable jaw, a movable jaw having a rack base projecting into said slot, and slidably arranged on said track, a screw nut freely turning on a fixed shaft across said slot and engaging said rack for adjusting said movable jaw, a stop slidably arranged on said shaft and engaging said nut and shaped to clear said rack and a lever handle spring-held to its open position and having an offset engaging said sliding stop and pivotally secured to the aforesaid handle.

Signed at the city of Toronto, this 13th day of December, 1920.

GEORGE BURFORD ANDERSON.
